US0D1112317S

(12) **United States Design Patent** (10) Patent No.: **US D1,112,317 S**
(45) Date of Patent: ** Feb. 10, 2026

(54) **DISPLAY SCREEN OR PORTION THEREOF WITH GRAPHICAL USER INTERFACE**

(71) Applicant: **Roland Corporation**, Shizuoka (JP)

(72) Inventor: **Marori Yoshioka**, Shizuoka (JP)

(73) Assignee: **Roland Corporation**, Shizuoka (JP)

(**) Term: **15 Years**

(21) Appl. No.: **29/985,105**

(22) Filed: **Jan. 16, 2025**

(30) **Foreign Application Priority Data**

Jul. 30, 2024 (JP) ..... 2024-015761 D

(51) LOC (15) Cl. **14-04**

(52) U.S. Cl.

USPC **D14/489**

(58) **Field of Classification Search**

USPC D14/485-495

CPC .. G06F 3/0481; G06F 3/0482; G06F 3/04817;
G06F 3/04886

See application file for complete search history.
